UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 12, 1926. Serial No. 128,823.

My invention relates to railway traffic controlling apparatus, and particularly to apparatus of the type comprising train carried governing means controlled by energy received from the trackway. More particularly my present invention relates to the trackway portion of such apparatus.

In at least one form of railway traffic controlling apparatus of the type described, 10 alternating track circuit current is supplied to the track rails for the control of trackway governing means, and alternating train controlling current is supplied to the rails for the control of train carried governing 15 means. One feature of my present invention is the provision, in systems of this character, of means for preventing improper operation of the trackway governing means by the train controlling current.

20 I will describe one form of trackway apparatus embodying my invention, and will then point out the novel features thereof in claims.

The accompanying drawing is a diagrammatic view illustrating one form of trackway apparatus embodying my invention.

Referring to this drawing, the reference characters 1 and 1^a designate the track rails of a stretch of railway track over which 30 traffic normally moves in the direction indicated by the arrow. These rails are divided, by means of insulated joints 2, into a plurality of successive track sections, only one of which, A—B, is shown in the drawing.

35 The rails of section A—B are supplied with alternating track circuit current from a transformer D having its secondary 16 constantly connected across the rails adjacent the entrance end of the section through 40 the usual impedance 18. The primary 17 of transformer D is constantly supplied with alternating current from a suitable source such as an alternator N over line wires 11 and 11^a.

45 Located adjacent the exit end of the section is a transformer T comprising a magnetizable core 3 carrying two windings 4 and 5. The right-hand end of winding 4 is connected with rail 1^a, and the right-hand end 50 of winding 5 is connected with rail 1 adjacent the exit end of section A—B. The

free ends of windings 4 and 5 are connected with a balancing network 9. The windings are so arranged that the fluxes created in core 3 by track circuit current flowing 55 through these windings and the network 9 from the rails of section A—B are additive. The core 3 is also provided with a third winding 6, which is connected with winding 7 of a track relay R. The second winding 60 8 of the track relay is constantly supplied with alternating current from line wires 11 and 11^a. The flux created in core 3 due to track circuit current flowing in the track rails of section A—B from transformer D 65 therefore creates in winding 7 of track relay R a current of the same frequency as the track circuit current and relay R is responsive to such current to close its front contacts. Relay R is therefore energized by 70 track circuit current supplied from transformer D when section A—B is unoccupied, and may be used to control governing means not shown in the drawing in any desired manner.

75 Means are also provided for supplying the rails of the section with alternating train controlling current. As here shown the immediate source of such current is a transformer G having a primary 13 constantly 80 supplied with alternating current, from a separate source such as an alternator M, over line wires 10 and 10^a, but this arrangement is not essential. The secondary 12 of transformer G is connected with the mid-points 4^a and 5^a of windings 4 and 5, respectively, through a limiting resistance 15 and back contact 14 of relay R. The train controlling current supplied to the rails by transformer G may be of the same or of different frequency from the track circuit current supplied by transformer D.

85 The supply of train controlling current to the rails will usually be controlled in accordance with traffic conditions in advance. 90 As shown in the drawing each track section is provided with a trackway signal designated by the reference character S with a suitable exponent. Each such signal is controlled by means forming no part of my 100 present invention and omitted from the drawing for the sake of simplicity, in such

manner that the signal indicates proceed, caution or stop in accordance with traffic conditions in advance. Associated with signal S^B is a circuit controller K arranged to be closed only when signal S^B indicates proceed or caution. This circuit controller is inserted in circuit with secondary 12 of transformer G as here shown and it will therefore be seen that train controlling current 10 is supplied to transformer T only when relay R is de-energized, and when signal S^B indicates caution or proceed. Under these conditions current flows from the right-hand terminal of secondary 12 of transformer G 15 through wire 20, back contact 14 of relay R, wire 21, circuit controller K, wire 22, to the mid-point 4^a of winding 4, thence through the right-hand half of winding 4 to rail 1^a of section A—B, and from rail 1 of this section, 20 through the right-hand half of winding 5, resistance 15 and wire 23 back to secondary 12 of transformer G. The circuit just traced is provided with a branch which passes from wire 22, through the left-hand 25 half of winding 4, balancing net-work 9, and left-hand half of winding 5 to resistance 15. It will therefore be plain that train controlling current flows through the two halves of each of windings 4 and 5 in opposite directions. The balancing network 9 is a combination of resistors and reactors, and is so adjusted that its impedance is substantially equal to the impedance of the rails of section A—B in series at the frequency of 30 the train controlling current. As a result, the fluxes created in core 3 by currents in the two branch paths just traced are opposite in direction and substantially equal in magnitude. It follows that substantially no electric 35 motive force is induced in winding 6, and no current is supplied to relay R, as a result of train controlling current flowing in the windings of transformer T.

In explaining the operation of the apparatus as a whole I will first assume that section A—B is unoccupied. Track circuit current supplied to the rails by transformer D therefore energizes relay R so that back contact 14 is open and secondary 12 of transformer G is disconnected from transformer T. Under these conditions no train controlling current is supplied to the rails of the section. I will next assume that signal S^B indicates caution or proceed and that a train enters section A—B. The shunting effect of the wheels and axles of this train interrupts the supply of track circuit current to transformer T so that relay R becomes de-energized, thereby closing back contact 14 50 and supplying train controlling current to the rails of section A—B. But the operation of the transformer T and balancing network 9 prevents improper operation of the relay R by train controlling current.

The train controlling current supplied to

the rails of the section may be used to control train carried governing means of any suitable form. Train carried governing means responsive to alternating train controlling current in the trackway is usually 70 controlled through the medium of a receiver carried on the train in advance of the forward axle. With such apparatus it is essential with the train controlling current be supplied to the trackway from a point in 75 advance of the train. One advantage of my invention is that train controlling current can be supplied to the exit end of a track section which is provided with a track relay also receiving track circuit current from the 80 rails of the section adjacent the exit end thereof without any danger of improper operation of the relay by train controlling current.

Although I have herein shown and described only one form of railway traffic controlling apparatus embodying my invention it is understood that various changes and modifications may be made therein within the scope of the appended claims without departing from the spirit and scope of my invention.

Having thus described my invention, what I claim is:

1. In combination with a stretch of railway track, a source of alternating track circuit current connected with the rails of such section, a transformer having two windings connected in series with said rails, a source of alternating train controlling current connected with intermediate points on said two windings, a track relay, and a third winding on said transformer for supplying said relay with track circuit current but not with train controlling current. 95

2. In combination with a stretch of railway track, a source of alternating track circuit current connected across the rails adjacent one end of said section, a transformer having two windings one terminal of each winding being connected with one rail adjacent the other end of the stretch, a source of alternating train controlling current connected with the mid-points of said windings, 100 a balancing network having substantially the same impedance at the frequency of said train controlling current as the rails of the stretch in series and connected across the free terminals of said windings, a track relay, 105 and a third winding on said transformer connected with said relay.

3. In combination with a stretch of railway track, a source of alternating track circuit current connected across the rails adjacent one end of said section, a transformer having two windings one terminal of each winding being connected with one rail adjacent the other end of the stretch, a balancing network connected across the free terminals of said windings, a track relay, a third 115

winding on said transformer connected with said track relay, a source of alternating train controlling current, and means for connecting such last-mentioned source with the mid-
5 points of said two windings respectively when said track relay is de-energized.

4. In combination, with a stretch of railway track, a source of alternating track circuit current connected across the rails adja-
10 cent one end of the section, a track relay, a source of alternating train controlling cur-

rent, and means including a transformer and a balancing network for at times supplying the rails adjacent the other end of said stretch with current from the last-mentioned source, such means permitting the supply of track circuit current to said relay from the rails of the stretch but preventing the supply of trains controlling current to such relay.

15 In testimony whereof I affix my signature.

SAMUEL M. LUCAS.
